The ornamental design for a short range target cap, as shown and described.

DESCRIPTION

FIG. 1 is a top perspective view of the short range target cap showing my new design together with broken lines representing its environment;

FIG. 2 is a top perspective view similar to FIG. 1 but without the environmental structures;

FIG. 3 is a bottom perspective view thereof;

FIG. 4 is a front elevational view thereof, whereby the opposing rear elevation view is a mirror image;

FIG. 5 is a side elevational view thereof, whereby the opposing side view is a mirror image;

FIG. 6 is a top plan view thereof; and,

FIG. 7 is a bottom plan view thereof.

The broken lines showing the environmental structure in FIG. 1 and portions of the short range target cap in FIGS. 1–3, 6 and 7 are for illustrative purposes only and form no part of the claimed design.
